JOHN L. CREVELING, OF NEW YORK, N. Y., ASSIGNOR TO SAFETY CAR HEATING AND LIGHTING COMPANY, A CORPORATION OF NEW JERSEY.

ELECTRIC REGULATION.

1,177,686.

Specification of Letters Patent.

Patented Apr. 4, 1916.

Application filed August 21, 1911, Serial No. 645,251. Renewed August 6, 1912. Serial No. 713,678.

To all whom it may concern:

Be it known that I, JOHN L. CREVELING, a resident of New York, in the county and State of New York, have invented certain new and useful Improvements in Electric Regulation, as set forth in the annexed specification and drawing, forming a part thereof.

My invention pertains to that class of electric regulation wherein it is desired to automatically regulate a dynamo, or generator, in a predetermined manner.

As my invention is particularly applicable to that class of electric systems wherein a generator is used to charge a storage battery and supply current to lamps or other translating devices, it will be described with reference to such a system.

In the drawing 1 represents a dynamo or generator provided with the usual field coil 2 having in series therewith two carbon piles 3 and 4 mechanically separated and electrically united by the lever, or movable member, 5 connected with the lever 6 pivoted as at 7. An adjustable spring 8 normally draws the lever 6 upwardly against the adjustable stop 9, while the motion that the lever may have in a downward direction is limited as by the adjustable stop 10. The lever 6 is provided at one extremity with the core of iron, or other magnetic material, indicated at 30.

11 is a bell-crank lever normally drawn in an upward direction as by the adjustable spring 12 in such manner as to tend to compress the carbon pile 3 and lower the resistance thereof. The lever 11 carries the core 13 of iron, or other magnetic material, and it is obvious that the resistance 3 may be made to depend upon the position of the said core.

14 is a lever normally drawn in an upward direction as by the adjustable spring 15 in such manner as to tend to compress the carbon pile 4 and lower the resistance thereof. The lever 14 carries the core 16 of iron, or other magnetic material, and the resistance of the pile 4 will obviously depend upon the position of the core 16.

17 represents the positive lead of the generator which is carried to one side of the storage battery 31 and then through the main 18, coil 19 and wire 20 to one side of the lamp regulating resistance 21, the oppo-

site side of which is connected as by the 55 wire 22 with one terminal of the translation circuit switch 23, from the other side of which the wire 22 continues to the positive terminals of the lamps or other translating devices indicated at 24. The negative 60 terminals of the translating devices 24 are connected with the lead 25 which is carried to the opposite side of the battery and connects with one side of the automatic switch 26, the opposite side of which is connected 65 through the solenoid 27 with the negative terminal of the generator.

28 is a fine winding, or solenoid, in shunt across the generator circuit as indicated.

The solenoid 19 is so arranged that energization of the same tends to draw the lever 6 downwardly against the action of spring 8 and decrease the resistance 3 and increase the resistance 4 as will hereinafter more plainly appear. The solenoid 27 is so arranged that energization of the same tends to draw the core 13 downwardly and increase the resistance 3. The solenoid 28 is so arranged that energization of the same tends to draw the core 16 downwardly and increase the resistance 4. The solenoid 29, in shunt across the translation circuit, tends to draw the core 32 downwardly in such manner as to tend to increase the resistance 21.

The switch indicated by 26 is preferably of the automatic variety adapted to close the circuit when the generator voltage is substantially equal to that of the storage battery, and as many switches of this character are well known in the art, the presence of one of this type of switch is merely indicated in a conventional manner, the particular form thereof forming no part of my present invention.

The operation of my invention is substantially as follows: If the generator be running at such voltage as to charge the storage battery, the switch 26 will be closed and current will flow from the generator through the lead 17, battery 31, lead 25, switch 26 and coil 27 to the generator and the generator may be regulated by proper manipulation of the resistances 3 and 4 in series with the field thereof, and I so adjust the spring 12 that when the maximum desired current is flowing in the coil 27, any excess in current will cause the lever 11 to

be depressed against the action of spring 12 so as to increase the resistance of the carbon pile 3 and prevent the generator output from exceeding its predetermined limit. If 5 now the battery be charged at this desired maximum and until its voltage has risen to the maximum voltage desired to have impressed across its terminals, I then so adjust the spring 15 that this voltage will not 10 be exceeded owing to the action of the coil 28 which upon any excess will depress the lever 14 and increase the resistance 4 in such manner as to prevent the generator voltage rising above this predetermined 15 limit. If the voltage now be held at this limit and the battery voltage rise still farther, the charging current will, of course, decrease or taper off in a well-known manner. If now the lamp switch 23 be closed, 20 current will flow through the translating devices and also through the coil 29, and I so adjust the lamp regulator that the coil 29, by operation of the resistance 21, will hold a constant voltage upon the translation 25 circuit in a well-known manner. The current flowing to the translating devices will pass through the coil 19 and tend to draw the lever 6 downwardly and swing the member 5 in a left-handed direction, the effect of which is to tend to compact the carbon pile 3 or change the adjustment thereof in such manner that a higher current will 30 be held constant by the coil 27 and also its effect will be to decrease the compression 35 upon the pile 4 so as to alter the adjustment thereof in such manner that a lower voltage will be necessary across the coil 28 to cause the same to affect the generator to prevent the desired voltage from being exceeded. 40 In other words, the maximum of the current regulator will be increased and the maximum limit of the voltage regulator will be decreased when the lamp load is thrown on. By properly adjusting the spring 8 and dimensioning the parts of the regulator, I 45 cause the adjustment of the two regulators to be affected in accordance with the load upon the translation circuit. With this arrangement it will be obvious that when the lamp circuit load is on, the generator will be caused, if regulated for current, to deliver a larger current than when the translation circuit is inoperative. Also, if the 50 system be regulated in accordance with voltage changes and the lamp circuit load be on, the voltage across the generator, which is held constant, will be less than that when the translation circuit load is off, and there will be less drop across the lamp 55 regulator and less waste of energy than if the maximum voltage were maintained across the generator with the lamp load on.

From the foregoing it will be obvious that I have produced a system of regulation 60 wherein a dynamo is regulated both in re-

sponse to current fluctuations and in response to voltage fluctuations and that I have provided means whereby the adjustment of the regulator for both these factors is altered in accordance with the load upon 70 the translation circuit.

I do not wish in any way to limit myself to the exact details of construction nor exact mode of operation set forth in the foregoing specification which are given merely 75 to illustrate one type of system embodying the essentials of my invention, for it is obvious that wide departure may be made in the way of details without departing from the spirit and scope of my invention which 80 is as set forth in the following claims:

1. Means for regulating a generator comprehending a regulating element, and means for operating the same in response to current fluctuations; a regulating element, and 85 means for operating the same in response to voltage fluctuations; and means for simultaneously affecting the adjustment of said elements.

2. Means for regulating a generator comprehending a regulating element, and means for operating the same in response to current fluctuations; a regulating element, and means for operating the same in response to voltage fluctuations; and automatic means 95 for simultaneously affecting the adjustment of said elements.

3. The combination with a generator and translation circuit; of means for regulating the generator comprehending regulating 100 means affected by current fluctuations; regulating means affected by voltage fluctuations; and means for varying the adjustment of both the current and voltage operated means responsive to fluctuations in the 105 translation circuit.

4. The combination with a generator and a work circuit; of means for regulating the generator comprehending a regulating element and means for operating the same in response to current fluctuations; a regulating element and means for operating the same in response to voltage fluctuations; means for affecting both of said elements; and means for operating said last named 110 means in response to a characteristic of the work circuit.

5. In an electrical system, a generator; a work circuit and its translating devices; a carbon pile resistance for regulating the generator; a coil for controlling said resistance responsive to current fluctuations; a second carbon pile resistance for regulating the generator; a coil for controlling said second resistance responsive to voltage fluctuations; a carbon pile rheostat in the work circuit for regulating the potential at the translating devices; a coil for controlling the action of said rheostat responsive to voltage fluctuations; and means whereby said 125 130

rheostat regulates the effect of said current and voltage coils on their respective carbon pile resistances.

6. In an electrical system, a generator; a work circuit supplied thereby; translating devices in the work circuit; a rheostat for regulating the generator; means for controlling said rheostat responsive to current fluctuations; a second rheostat for regulating the generator; means for controlling said second rheostat responsive to voltage fluctuations; a variable resistance for regulating the voltage at the translating devices; a coil responsive to voltage fluctuations for controlling said variable resistance; and means whereby said variable resistance acts to regulate the effect of both the said controlling means on their respective rheostats in the regulation of the generator.

20 7. In an electrical system, a generator; a storage battery and work circuit supplied thereby; translating devices in the work circuit; a rheostat for regulating the generator; means for controlling said rheostat responsive to current fluctuations; a second rheostat for regulating the generator; means for controlling said rheostat responsive to voltage fluctuations; a variable resistance for regulating the voltage at the translating devices; a coil responsive to voltage fluctuations for controlling said variable resistance; and means whereby said variable resistance acts to regulate the effect of both the said controlling means on their respective rheostats in the regulation of the generator to cut down the battery current upon certain increases in voltage of the battery.

8. In an electrical system, a main generator; a work circuit connected to be supplied thereby; means for regulating the generator responsive to current fluctuations; means for regulating the generator responsive to voltage fluctuations; means for independently regulating the voltage applied to the work circuit responsive to voltage fluctuations; and means whereby said last mentioned means will govern the effect of both the first mentioned regulating means in the regulation of the generator.

50 9. In an electrical system, a work circuit; a main generator; a shunt field winding therefor; a carbon pile resistance in series with said field winding; an electro-magnetic device for controlling said carbon pile including a coil responsive to variations in generator current for controlling said device to regulate the generator; a carbon pile resistance in series with said field winding; an electromagnetic device for controlling said carbon pile including a coil responsive to variations in generator voltage for controlling said device to regulate the generator; a regulating device for regulating the voltage at the work circuit; and means whereby said regulating device governs the effect of said

electromagnetic devices in the control of their respective carbon piles.

10. In an electrical system, a work circuit with its translating devices; a main generator for supplying the same; a rheostat for regulating the main generator; an electromagnetic device for controlling said rheostat, including a coil responsive to variations in the generator current for controlling said device, and a coil responsive to variations in the generator voltage for controlling said device; regulating means for regulating the voltage on the translating devices; and means whereby said regulating means governs the effect of the said coils in the control of their respective rheostats.

11. The combination with a generator; current actuated regulating means therefor; voltage actuated regulating means therefor; of a translation circuit; a regulator for the translation circuit; and means whereby the operation of said translation circuit regulator affects directly both the generator regulating means.

90 12. The combination with a generator and a regulator therefor, comprehending regulating means and means for operating the same responsive to current fluctuations and responsive to voltage fluctuations; of a translation circuit; means whereby current in said translation circuit affects the generator regulating means; and means for controlling the current in said translation circuit and thereby regulating the effect of both the current and voltage fluctuations in said operating means.

13. In an electrical system, a generator; a work circuit and its translating devices; a resistance for regulating the generator; a coil for controlling said resistance responsive to current fluctuations; a second resistance for regulating the generator, a coil for controlling said resistance responsive to voltage fluctuations; a rheostat in the work circuit for regulating the potential at the translating devices; a coil for controlling the action of said rheostat responsive to voltage fluctuations; and means whereby said rheostat regulates the effect of said current and voltage coils in the control of their respective resistances.

120 14. In an electrical system, a work circuit; a main generator; a shunt field winding therefor; a resistance in series with said field winding; an electromagnetic device for controlling said resistance including a coil responsive to variations in generator current for controlling said device to regulate the generator; a second resistance in series with said field winding; an electromagnetic device for controlling said resistance including a coil responsive to variations in generator voltage for controlling said device to regulate the generator; a regulating device

for regulating the voltage at the work circuit; and means whereby said regulating device regulates the effect of said electromagnetic devices in the control of their respective resistances.

15. The combination with a generator; a generator circuit; a work circuit; means operated by variations in voltage of the work circuit tending to hold the same constant; and means affected thereby for separately regulating the voltage and current of the generator.

16. A system of electrical distribution comprehending a generator; a generator circuit; a work circuit; voltage operated means for holding the voltage across the work circuit substantially constant throughout variations in voltage across the generator circuit; and means affected by said first means thereby for separately preventing the generator voltage and current from exceeding predetermined limits.

17. A system of electrical distribution comprehending a generator; a translating circuit; means in series with the translating circuit capable of altering the voltage thereof; means responsive to changes in voltage of the translating circuit for operating said voltage altering means to hold the voltage across the translation circuit substantially constant throughout certain changes in generator voltage; regulating means for the generator responsive to current and voltage fluctuations; and means whereby the means responsive to voltage fluctuations of the translating circuit affects the current and voltage regulating means, so as to regulate

the current and voltage of the generator separately.

18. A system of electrical distribution 40 comprehending a generator; a work circuit; means inserted in the work circuit affecting the voltage thereof; means for operating the same affected by the voltage of the work circuit; means for regulating the generator 45 responsive to voltage fluctuations and to current fluctuations; and means whereby the means for affecting the work circuit affects the means for regulating the generator to govern the current and voltage of the 50 generator separately.

19. The combination of a generator and means for regulating the same; means for operating the regulating means; additional means for operating the regulating means; 55 and means for affecting one of said operating means and oppositely affecting the other of said means.

20. The combination of a generator and means for regulating the same; means for 60 operating the regulating means in response to current fluctuations; means for operating the regulating means in response to voltage fluctuations; and means for affecting the first-named operating means so as 65 to raise the standard of current regulation and the second-named operating means so as to decrease the standard of voltage regulation.

JOHN L. CREVELING.
